United States Patent Office

Des. 221,400
Patented Aug. 10, 1971

221,400

FLOOR MAT

Thomas P. O'Donnell, Kings County, N.Y.
(220 Highland Blvd., Brooklyn, N.Y. 11207)

Filed Oct. 28, 1968, Ser. No. 14,195

Term of patent 14 years

Int. Cl. D6—05

U.S. Cl. D44—31

FIG. 1

FIG. 2

FIG. 3

FIG. 1 is a perspective view of a floor mat showing my new design;

FIG. 2 is a front elevational view; and
FIG. 3 is a right side elevational view.

I claim:

The ornamental design for a floor mat, as shown.
